UNITED STATES PATENT OFFICE.

EDWIN C. HEATHCOTE, OF BROOKLYN, NEW YORK.

DESIGN FOR AN EMBLEM, PIN, BUTTON, WATCH-CHARM, MEDAL, OR SIMILAR ARTICLE.

55,790.

Specification for Design.

Patented July 13, 1920.

Application filed March 7, 1919. Serial No. 281,313. Term of patent 3½ years.

To all whom it may concern:

Be it known that I, EDWIN C. HEATHCOTE, a citizen of the United States, residing at the city of New York, borough of Brooklyn, Kings county, in the State of New York, have invented a new, original, and ornamental Design for an Emblem, Pin, Button, Watch-Charms, Medal, or Similar Article, of which the following is a specification, reference being had to the accompanying drawing, forming part thereof.

In said drawing the figure is a face view of a watch-charm or medal, embodying or incorporating my said design.

I claim:

The ornamental design for an emblem, pin, button, watch-charm, medal, or similar article, as shown.

EDWIN C. HEATHCOTE.
